UNITED STATES PATENT OFFICE.

ISAAC F. HALL, OF DAYTON, OHIO.

LIGHT-SUPPORT.

1,380,528

Specification of Letters Patent. Patented Feb. 10, 1920.

Application filed October 27, 1919. Serial No. 333,531.

To all whom it may concern:

Be it known that I, ISAAC F. HALL, a citizen of the United States, residing at Dayton, in the county of Montgomery and State of Ohio, have invented new and useful Improvements in Light-Supports, of which the following is a specification.

In setting signals on semaphore posts in railway systems it is necessary for the attendants to climb a ladder which is frequently from 20 to 30 feet high. This is a laborious and dangerous undertaking and also requires a considerable amount of time.

It is the object of the present invention to produce a means whereby a signal lamp may be raised and supported upon a semaphore post from the ground. The improvement also contemplates a simple device in which the same means for setting the lamp on the post is employed for lowering the lamp when the same is to be lighted or extinguished, or the bowl is to be supplied with oil, or when the wick is to be regulated, etc.

The foregoing objects and others which will appear as the nature of the invention is better understood, may be accomplished by a construction, combination and operative arrangement of parts such as is illustrated by the accompanying drawings, it being understood, however, that the nature of the invention is such as to render the same susceptible to various modifications, all of which falling within the scope of what is claimed.

35 In the drawings:

Figure 1 is an elevation showing the arrangement of parts when the signal lamp is on the ground, the dotted lines indicating the position of the lamp when the same is elevated, but before the lamp is positioned on the post.

Fig. 2 is a similar view showing the lamp positioned on the post.

Fig. 3 is a similar view showing the arrangement of parts when the lamp is raised above the post prior to seating the same thereon, the dotted lines indicating the manner in which the lamp is swung away from the post, as when the lamp is to be lowered.

50 Fig. 4 is a rear elevation of the device.

Fig. 5 is a sectional view approximately on the line 5—5 of Fig. 4, the lamp being seated on the post.

Referring now to the drawings in detail, 55 the numeral 1 designates a semaphore post. Encircling the post at the top thereof, and

secured thereto is a band 2. This band has one of its ends provided with an extension 3, and the other end of the said extension is formed with an upstanding plate 4. The upper end of the plate 4 is provided with a horizontally outstanding arm 5, the said arm, as well as the upper portion of the plate being centrally bifurcated. Pivots secured, as at 6 between the arms provided by the horizontal angular extension 5 is a grooved wheel 7. The arms 5, inward of the wheel 7 have upstanding lugs 8 between which is pivoted, as at 9 a dog 10.

On the sides of the plate 4, a suitable distance above the top of the post 1 is a pair of oppositely disposed brackets 11, which are directed toward the post. Each of the brackets is of a similar formation having the upper corners thereof cut at a curvature to provide rounded edges 12 that terminate in straight shoulders 13. The brackets have their body portions provided with vertically disposed aligned slots 14, and the inner walls of these slots are preferably flushed with the inner face of the plate 4. Directly above the slots 14, the brackets 11 are notched as at 15.

On the band 2 preferably diametrically opposite its upstanding plate 4 is a peg 16.

Between the spaced brackets 11 is an arm 17. This arm, adjacent the lower end thereof is provided with laterally extending studs 18 which are received in the slots 14, while the said arms are provided with additional studs 19 spaced a suitable distance from the studs 18 which are designed to be received in the notches 15 of the brackets when the arm 17 is to be held locked against the plate 4, in a manner and for a purpose to be presently described.

The arm 17 adjacent its outer end and upon its outer face is provided with a transverse notch 20, to receive a pointed end of the dog 10 when the said notch is brought opposite the dog and whereby the arm 17 is held against gravitating by its own weight downward of the plate 4.

On the inner face of the arm 17, below the notch 20 there is formed or secured a right angular extension 21. This extension really is in the nature of two spaced members, the inner faces of which being flush with the walls provided by the bifurcated upper end of the plate 5, and by a bifurcated portion 22 in the arm 17. The spaced parallel members provided by the extension 21,

are however centrally connected by a cross piece 23, and the said members inward of the cross piece have down standing lugs 24 between which there is pivoted, as at 25, 5 a grooved wheel 26. The arms provided by the extension 22 at their outer ends have one of their corners formed with additional lugs provided at the juncture of the said members with an angle extension 27 that is integrally formed thereon, and which is directed 10 in the same plane as the portion of the arm 17 above the angle extension 21. The referred to lugs have passed through suitable openings therein a shaft 28 on which is bevelled a grooved wheel 29 that is positioned 15 between the arms of the member 21. The shaft 28 extends a suitable distance beyond the sides of the member 21, and these ends provide pivots for the eye portion 29 of a 20 depending slotted guide 30.

The signal lamp is indicated by the numeral 31 and is provided on one of its faces with a socket 32. The lamp is provided with the usual bail 33 to which is connected a flexible element in the nature of a strap or cable 34. The cable is trained through the hollow guide 30, around the grooved wheel 29, under the grooved wheel 24 and over the grooved wheel 7. The flexible member 34 is of a length to permit of the same being secured to the staple 35 on the post 1 adjacent the ground, when the said cable is not in operation.

The operation of the device may be briefly 35 described as follows:

We will suppose the lamp to be on the ground, as in Fig. 1. In this position the arm 17 has its lugs 19 resting on the shoulders 13 of the brackets. A pull on the flexible element or cable 34 will elevate the lamp causing the bail thereof to contact with the pivoted guide which being secured to the angle portion of the frame provided by the arms 17 and its extension 21 will 40 swing the said frame upwardly, causing the lugs 19 to travel over the rounded surfaces 12 of the brackets 11 and also causing the lugs 18 to move downwardly in the slots 14. When the arm 17 of the frame is 45 brought against the inner face of the plate 4, the upper edge of the said arm will be disposed below the dog 10. It is to be understood that the frame is heavier than the lamp, and a slackening of the cable will 50 cause the descent of the frame on the arm so that the lugs 19, which are really the trunnions for the swinging frame will travel downwardly through the slots 14 and the lugs 19 will be received in the notches 15 55 of the brackets. This locks the frame to the supporting means therefor, which, of course, constitute the arm 4 and the brackets 11. A still further slackening of the cable causes 60 the lamp to descend by gravity, and as the 65 socket 32 thereof is positioned in alignment

with the peg 16, the said peg will be received in the socket when the bottom of the lamp rests on the top of the post, and thus the lamp is securely sustained on the post. When the lamp is to be lowered, a downward pull is exerted upon the cable 34 which causes the frame to be moved upwardly until the trunnions 18 contact with the upper walls of the slots 14. This arranges the dog 10 in the socket 20. A further pull on the 70 cable raises the lamp above the post. The dog 10 has a tendency to force the frame outward of the plate 4 of the support for the frame so that a slackening of the cable permits of the frame being swung outwardly 75 of the support for the frame and also allows the frame to assume its initial horizontal position and the lamp to be lowered to the ground.

From the foregoing description, taken in 80 connection with the drawings, the construction and operation of the device will it is thought be perfectly apparent to those skilled in the art to which such inventions relate without departing from the detail 85 description of the invention.

Having thus described my invention what I claim as new is:—

1. In a device for the purpose set forth, a post, a frame supporting member on the 95 top thereof carrying an upstanding peg, a frame arranged for vertical and for swinging movement on said support, grooved wheels carried by the frame and by the support, a flexible element trained therearound and a lamp provided with a socket secured to said element, as and for the purpose set forth.

2. In combination with a post, of a frame supporting member secured at the top thereof and said member carrying an upstanding peg, a frame disposed for vertical and swinging movement on the support, means carried by the support for engagement with the frame to move the same outward and to 100 permit of the downward swinging of the frame when the said frame is brought to one position, grooved wheels carried by the frame and support, a flexible element trained therearound, and a signal lamp having a socket to receive the peg secured to said flexible element, as and for the purpose 105 set forth.

3. In combination with a post, of a vertically disposed frame supporting member secured to the top thereof and an upstanding peg on said member at its juncture with the post, brackets carried by said member, said brackets having their upper surfaces curved and the said curved portions terminating in 120 shoulders, a frame including an arm disposed between the brackets for vertical and swinging movement with respect thereto, elements on the arm for limiting the vertical movement thereof, other elements on 125 130

said arm for ragging over the rounded portion, the curved portions of the brackets and for resting on the shoulders thereof, when the arm of the frame is sustained 5 horizontally, grooved wheels carried by the support and by the frame, a flexible element trained therearound, and a lamp having the socket to receive the post secured to the flexible element as and for the purpose set 10 forth.

4. In combination with a post, of a frame support, secured to the top thereof, an up- 15 standing peg carried by the support, a frame disposed for vertical and swinging movement on the support, means for limit- 20 ing both the vertical and swinging move- 25 ments of the frame, means for directing the frame away from the support when the said frame is in one position, means for locking the frame on the support when the latter is in a second position, grooved wheels carried by the support and frame, a flex- 30 ible element trained therearound, and a lamp having a socket to receive the peg when the said lamp is elevated over the post, se- 35 cured to the flexible element.

5. In combination with a semaphore post, and a lamp having a socket designed to be

supported on the top of the post, of a band secured on the post at the top thereof, said 30 band having an upstanding peg thereon, and having an extension opposite the peg termin- 35 ating in an upstanding arm, a pivoted dog on the upper end of the arm, a grooved wheel journaled upward of the dog, brack- 40 ets secured to the sides of the arm, said brackets having alining vertically disposed slots, and their upper edges provided with alining notches above the slots, the upper 45 corners of the brackets being rounded and 50 terminating in outstanding shoulders, a frame including an arm having spaced pairs of lugs on the sides thereof and the lower lugs being received in the slots of the brackets, said frame having an angle ex- tension provided with spaced grooved wheels and with a depending pivoted guide, a flex- 55 ible element secured to the lamp, trained through the guide and around the mentioned grooved wheels, and means for securing the free end of the flexible element to the sema- 60 phore post, all as and for the purpose set forth.

In testimony whereof I affix my signature.

ISAAC F. HALL.
